UNITED STATES PATENT OFFICE.

ALBERT D. SANDERS AND WILLIAM H. LLOYD, OF CHICAGO, ILLINOIS, ASSIGNEES TO FEDERAL-HUBER COMPANY, OF CHICAGO, ILLINOIS, A CORPORATION OF ILLINOIS.

DESIGN FOR A WATER-CLOSET BOWL.

41,333.

Specification for Design.

Patented Apr. 25, 1911.

Application filed January 14, 1910. Serial No. 538,151. Term of patent 7 years.

To all whom it may concern:

Be it known that we, ALBERT D. SANDERS and WILLIAM H. LLOYD, citizens of the United States, residing at Chicago, in the county of Cook and State of Illinois, have invented a certain new, original, and ornamental Design for Water-Closet Bowls, of which the following is a specification, reference being had to the accompanying drawing, forming part thereof.

Figure 1 is a side elevation of a water closet bowl showing our new design. Fig. 2 is a rear elevation of a water closet bowl

setting forth our new and original design. Fig. 3 is a side perspective view of a water closet bowl showing our new and original design.

We claim:—

The ornamental design for a water closet bowl, substantially as shown.

ALBERT D. SANDERS.
WILLIAM H. LLOYD.
